UNITED STATES PATENT OFFICE.

THOMAS J. FLAGG, OF NEW YORK, N. Y., ASSIGNOR TO FISK, CLARK
& FLAGG, OF SAME PLACE.

DESIGN FOR A MADE-UP SCARF.

SPECIFICATION forming part of Design No. 15,298, dated August 19, 1884.

Application filed May 3, 1884. Term of patent 14 years.

To all whom it may concern:

Be it known that I, THOMAS J. FLAGG, of the city, county, and State of New York, have invented a new and original Design for a Made-up Scarf; and I do hereby declare that the following is a full and exact description thereof, reference being had to the accompanying drawing, and to the letters of reference marked thereon, making a part of this specification.

The principal feature of my design is found in the configuration of the outer apron, S, of the scarf, which, as represented in the drawing, is bounded on one side by the zigzag line A B C D, presenting two outward angles, B and D, and an intermediate re-entrant angle, C, and on the other by a long line, D' F, extending parallel with the line B C from a point opposite the termination D of the lateral line A B C D to a point determined by the intersection of said line D' F with an imaginary line xx , drawn midway between the points D D', parallel with an imaginary line drawn from the angle B to the angle D of the lateral line A B C D. The upper ends of the two side lines, D' F, and A B C D are united by a straight line, F A, and their lower ends may be connected by equal lines D E and D' E, intersecting to form an angle, E, on the imaginary central line, xx ; but the form of the lower end of the scarf between said points D and D' is not an essential feature of the design, and may be varied to include either a straight line or a curved line connecting said two points D D', as illustrated by dotted lines in the drawings. The design for the scarf is completed by an upper line, A A', drawn from the point A, at right angles with the imaginary central line, xx , far enough to be bisected by said line in conjunction with a line, A' F, defining the center piece, U, of the scarf, and with the side lines, A' B' and B' C', equal in length to the two lines A B and B C on the opposite sides

of the scarf, and which form by their intersection an angle, B', the counterpart of the angle B, and by a line, A' F, the line B' C' being made to intersect the line D' F at a point immediately opposite the re-entrant angle C in the lateral zigzag line A B C D, and thus complete not only the outline of the entire scarf, 50 but also of its inner apron, T.

The design may be ornamented and relieved of stiffness or flatness in appearance by means of folds, plaits, or puffs G G, extending inward from the side lines, A B A' B', as illustrated in the drawing.

I claim—

1. The design for a made-up scarf, herein shown and described, which consists of the two broken lateral lines A B C D and D F A, 60 intersecting at A, and united at their lower ends by a line connecting the points D D', to define the outline of the outer apron of the scarf, and the upper line, A A', side lines, A' B' and B' C', and inner line, A F, which define the inner apron, T, and center piece, U, of the scarf, and complete its configuration.

2. The design for a made-up scarf, herein shown and described, which consists of the two broken lateral lines A B C D and D F A, 70 intersecting at A, and united at their lower ends by a line connecting the points D D', to define the outline of the outer apron of the scarf, the upper line, A A', side lines, A' B' and B' C', and inner line, A' F, which define 75 the inner apron, T, and center piece, U, of the scarf, and complete its configuration, and the ornamentation G G.

In testimony whereof I have signed my name to this specification in the presence of two subscribing witnesses.

THOMAS J. FLAGG.
